FRANK A. BICKNELL, OF FLORENCE, AND JULIUS F. BEST, OF HAYDENVILLE, MASSACHUSETTS, ASSIGNEES TO PURO SANITARY DRINKING FOUNTAIN COMPANY, A CO-PARTNERSHIP COMPOSED OF CHRISTIAN J. HILLIS AND REUBEN B. HILLIS, OF HAYDENVILLE, MASSACHUSETTS

BUBLER TIP

Application filed September 12, 1928. Serial No. 305,451.

Our invention relates to improvements in drinking fountains of the bubbler type, and more particularly to the portions known as tips of such fountains, such tips being the elements through which the water is finally delivered for consumption.

Two objects are attained by our invention: First, the strainer or filter, which forms a part of the bubbler tip, is automatically cleaned during any and all periods of use of said tip; and, second, contamination of the tip by means of the finger or some other object applied to the rim of the outlet orifice, and squirting water by placing such finger or object over said orifice, as may be done with the ordinary tip, are prevented. These are important advantages because of the increased sanitary condition in which the tip is maintained at all times, and the prevention of squirting of water about by small boys and malicious persons.

The filter prevents all foreign matter of any appreciable size whatsoever from escaping to the outlet of the tip where it would be liable to be taken in by a person drinking.

Other objects and advantages will appear in the course of the following description.

We attain the objects and secure the advantages of our invention by the means illustrated in the accompanying drawings, in which—

Figure 1 is a top plan of a bubbler tip which embodies a practical form of our invention; Fig. 2, a side elevation of said tip; Fig. 3, a central, vertical section through the tip, and, Fig. 4, a central vertical section through a modified anti-squirt member.

Similar reference characters designate similar parts throughout the several views.

This tip is designed to be mounted on the supply nipple of a drinking fountain, over a bowl which receives the waste water, but, inasmuch as such nipple and bowl are not material parts of the present invention, and may vary extensively, they are not shown in connection herewith. In fact, it is to be understood that the tip may be mounted on any suitable nipple or supply pipe, and all other parts and members of a drinking fountain dispensed with. There is usually a valve,

for letting on and shutting off the water to and from the tip, located in the supply pipe on which the tip is directly or indirectly mounted, but it is not deemed necessary to illustrate such valve here.

Our bubbler tip comprises a base 1, a shell 2, and a strainer or filter 3.

The base 1 is internally screw threaded at 4 to enable said base to be mounted on and engaged with the supply nipple of a drinking fountain, or any supply nipple or pipe, and has its intermediate portion externally screw threaded to receive an internally screw-threaded part at the bottom of the shell 2, there being an exterior shoulder 5 on said base below said screw-threaded part to receive and seat the under side of said shell. The upper portion of the base 1 is in the form of a dome 6 of less diameter than the portions of said base which are below. From the axial center of the dome 6 rises a rod 7. Within the base 1 above the screw threads 4 is what we term a filter chamber 8, and within the dome 6 is what we term a collection chamber 9. The chambers 8 and 9 open into each other, and said first-named chamber is in open communication with the open bottom of the base 1. In the wall of the chamber 9 is a plurality of openings or ports 10. Within the base at the bottom of the chamber 8 is a shoulder 11. An oblique passage 12 is formed and arranged in the base 1 to open at one end below the shoulder 11 and at the other end outside of said base, said passage inclining from above downwardly and outwardly.

Besides the screw-threaded opening in the bottom of the shell 2, said shell has a discharge opening or orifice 13 at the top. The rod 7 extends upwardly from the dome 6 through the orifice 13 to a point some little distance above the top of said orifice, or far enough to prevent covering or closing said orifice with the finger. The shell 2 is of substantially the shape illustrated in the drawings, and has therein a discharge chamber 14 into which the dome 6 extends and the chamber 9 opens through the ports 10.

The filter 3 may be made of fine wire-mesh or gauze, and is approximately hemispherical in shape, and hollow, and said filter is placed

in the chamber 8 with the bottom edge of said filter on the shoulder 11. When properly placed in the chamber 8, the filter rests at the bottom on the shoulder 11, and bears with its top portion against the annular rim at the open bottom of the chamber 9. The filter 3 is thus held securely in place in the chamber 8. There is a portion of the chamber 8 which surrounds a corresponding portion of the filter, and some of the water that passes through said filter enters this space outside without being able to enter the chamber 9. The chamber 8 must be of sufficient size to receive a filter properly proportioned to take care of the volume of water required to pass through the same, and also to provide the aforesaid outside space.

The mesh of the wire-gauze, of which the filter 3 is usually constructed, should be sufficiently fine to prevent sand, grit, scale, vegetable, and animal matter, etc., from passing through the same.

The ports 10 are located in the wall of the dome 6 at the bottom thereof, thus a compression space for the water entering the chamber 9 from below is left in the upper part of said chamber, whereby is insured a full and complete flow of water through said ports.

The discharge chamber 14 is shaped to concentrate and form into a round stream the whirling water which enters said chamber through the ports 10. This water is thrown upwardly in hollow formation until it arrives at the orifice 13 where is produced a circular column which passes through said orifice, rises some distance above the same, and then spreads out in all directions in the form of a mushroom or umbrella-shaped, drinking bubble. The water flows up around the rod 7, as said water approaches and passes through and above the orifice 13, and the bubble is formed or produced above the top of said rod.

The water entering the base 1 at the bottom, passes upwardly in said base, into and through the filter 3 into the chamber 9, and also into that portion of the chamber 8 which is outside of said filter. The water caught and held back in the chamber 8, by impinging against the top and sides of said chamber may return through the filter and, assist in cleaning the same. The passage 12 is also an important factor in keeping the filter 3 clean, due to the fact that the water in passing through the filter meets with some resistance when it strikes or encounters the same, and some of the water is thereby forced or thrown back or down and out through said passage. Thus a separate current may be established, that is, a current having a direction that is approximately opposite to that of the incoming current or volume, which separate current continuously washes the inner surface of and carries off all foreign mat-

ter caught by the filter, thereby tending to prevent any possibility of contamination.

The general operation of the bubbler tip is briefly described as follows:

Water, admitted at the bottom of the base 1, passes upwardly through the filter 3 into the chambers 8 and 9, through the ports 10 into the chamber 14, and through the orifice 13, around the rod 7, in the form of a cylindrical stream at the apex of which is a bubble of the shape and size required for drinking purposes. Some of the water passing through the filter 3 enters the restricted space in the chamber 9, which space is outside of said filter, and the water in said space is cushioned and may flow back through said filter and escape through the passage 12, so that said filter, not only is subjected to the action of the outgoing water, but also to the action of the water which may return from the chamber 8 through the filter, and to the action of the water, on the inside of the filter, which does not pass through the filter, but, taking a different course from that of the main volume, runs off through the passage 12. It is clear, therefore, that the outside and inside and practically all parts of the filter 3 are so thoroughly washed and cleaned, automatically as it were, by the water, there is almost no opportunity for the permanent, and hardly for the temporarily, lodgment thereon or therein, or for the permanent engagement therewith, of any foreign matter or substance, unless it be of the most minute and tenuous character.

When the water is shut off, the tip is thoroughly and completely drained through the ports 10, the strainer 3, and the passage 12, there then being a back flow from the chambers 14, 9, and 8 outside of the strainer.

The purpose of the rod 7 is to prevent any object from being placed over the orifice 13 for the purpose of squirting the water flowing through said orifice, and incidentally to discourage touching the shell 2 near the orifice. The rod 7 is, therefore an anti-squirt member, and its presence converts the appliance into an anti-squirt tip.

If desired, an open-top tube 15 may be substituted for the solid rod 7, in which event there should be an opening or port 16 at the base of said tube. With this anti-squirt member in place, the water enters the tube 15 from the chamber 14, through the port 16, and flows upwardly inside of said tube to emerge at the top and join the exterior stream. The port 16 also enables the water to flow down and drain out of the tube 15 into the chamber 14, when the supply is shut off, so that no water can stand in said tube to become contaminated.

Not alone the strainer, but the entire interior of the tip is left thoroughly clean and in a sanitary condition, so far as such condi-

tion is attainable through the medium of running water.

More or less change in the shape, size, construction, and arrangement of some or all of the parts of this bubbler tip, in addition to those hereinbefore specifically pointed out, may be made without departing from the spirit of our invention, or exceeding the scope of what is claimed.

10 We claim:

1. The combination, in a bubbler tip, with a base having therein a filter chamber and a collection chamber, the wall of which latter is perforated, and an anti-squirt member extending upwardly from the top of said collection chamber, of a shell mounted on said base, and having an outlet through which said member extends without filling the same, and an approximately hemispherical filter in said filter chamber.

2. The combination, in a bubbler tip, with a base having an oblique passage in the wall thereof, provided above said passage with an interior shoulder, and having a filter chamber above said shoulder and a collection chamber above said filter chamber and opening into the same, the wall of which collection chamber is perforated, and an anti-squirt member rising from the top of said collection chamber, of an approximately hemispherical filter on said shoulder in said filter chamber, which latter chamber has therein space outside of said filter, and a shell mounted on said base, and having an outlet through which said member extends without filling the same.

3. The combination, in a bubbler tip, with a base including a filter chamber and a collection chamber, the wall of the latter having an opening therethrough, an anti-squirt member extending upwardly from the top of said collection chamber, a shell mounted on said base having upwardly extending walls formed at the upper end thereof to provide an orifice around said anti-squirt member and the anti-squirt member extending beyond the walls forming the shell.
